(57) **CLAIM**

The ornamental design for a pet waste storage container as shown and described.

DESCRIPTION

FIG. 1 is a perspective view of the pet waste storage container showing the new design wherein its lid is closed. FIG. 2 is a perspective back view of the pet waste storage container showing the new design wherein its lid is closed. FIG. 3 is a perspective view of the pet waste storage container showing the new design wherein its lid is open. FIG. 4 is a back planar view of the pet waste storage container showing the new design wherein its lid is closed. FIG. 5 is a front planar view of the pet waste storage container showing the new design wherein its lid is closed. FIG. 6 is a left side view of the pet waste storage container showing the new design wherein its lid is closed. FIG. 7 is a right side view of the pet waste storage container showing the new design wherein its lid is closed.

FIG. 8 is a top view of the pet waste storage container showing the new design wherein its lid is closed; and, FIG. 9 is a bottom view of the pet waste storage container showing the new design.

The broken lines in the drawings depict portions of the pet waste storage container that form no part of the claimed design.
